UNITED STATES PATENT OFFICE.

GUY E. FARMER, OF ANAMOSA, IOWA.

ICE-CREAM GUN.

Application filed June 28, 1927. Serial No. 202,045.

This invention relates to measuring molds for ice cream and similar material and more particularly to molds equipped with an ejecting plunger.

5 A primary object of the invention is to provide a two-in-one apparatus consisting of a mold having a plunger with a handle which may be made stationary for pushing the mold down into the material to be measured and dispensed and which is readily released to convert it into an ejector for forcing out the measured product from the barrel.

This plunger may also be used as an inside 15 cleaner for the barrel or body of the mold by reciprocating it rapidly in a cleansing fluid.

Another object of the invention is to provide a mold of this character equipped with 20 a pivoted latch for locking the plunger against movement in the barrel, and which latch may be readily released and the contents of the mold ejected by easy operation of one hand.

25 The details of construction and arrangement of parts contemplated by this invention are disclosed in the accompanying drawing, forming part hereof and wherein a preferred embodiment of the invention is shown for purposes of illustration.

In the drawing similar reference characters refer to corresponding parts in the several views, of which:—

30 Fig. 1 is a perspective view of the mold embodying this invention with the plunger locking latch shown released and in open position, to adapt the plunger to be used as an ejector;

35 Fig. 2 is a longitudinal section with the latch released and the plunger shown at its extreme outward movement for ejecting the molded product; and

40 Fig. 3 is a side elevation showing the plunger in retracted position and the latch 45 in locking engagement to hold it retracted and to render the handle stationary.

This invention contemplates in the conversion of a reciprocable plunger-carried rod to perform the dual function of a plunger-operating device or a handle to force the mold into the material to be molded, the provision of a pivoted latch to lock the rod

against movement in the mold body or barrel and which may be quickly released thereby adapting the rod to accomplish this dual 55 function.

In that connection, it is to be noted that one of the distinctive features of the invention resides in so constructing and mounting the latch member that it may be speedily 60 swung into locking position and when so locked will securely and reliably hold the plunger against movement and yet may be quickly and easily released with one hand.

In the embodiment illustrated, the mold 65 constituting this invention comprises a tubular barrel 1 which may be of any desired cross sectional configuration, being here shown cylindrical and which has secured to its upper end a bail-like member 2, the cross 70 bar 3 of which is apertured to loosely receive a plunger-carried rod 11, the plunger 10 being loosely mounted to slide within the barrel. This barrel 1 which is open at both ends is preferably provided on its outer face 75 intermediate said ends with an angular bead 4 forming hand grips to facilitate holding of the barrel against slippage during operation of the device.

The plunger rod 11 is provided with a 80 stop 12 adapted to engage the lower face of the cross bar 3 of yoke 2 to limit the inward or upward movement of the plunger 10 as is shown clearly in Fig. 3. This rod 11 is also equipped at its upper end with a hand 85 grip 13 to facilitate the manipulation of the mold and the plunger within the mold.

A latch or trigger 15 is pivotally mounted 90 at one end on the rod 11 at a point adjacent the handle 13 thereof and as shown is composed of two metal strips or bars 16 and 17 which straddle the rod 11 and is pivoted thereto as shown at 18. The free ends of these strips 16 and 17 are connected by a U-shaped clip 19 which extends over said 95 ends and is riveted thereto and performs the function of a connector and a spacer for the strips and also as a stop or abutment to engage the cross bar 3 of the yoke 2 when the latch is in closed position as shown clearly in Fig. 3, thereby locking the plunger in retracted position, the stop 12 on the rod 11 co-operating with the stop 19 to so hold 100 these parts.

Releasing lugs or finger grips 20 and 21 project laterally from opposite sides of the latch 15 intermediate the ends thereof and said lugs as shown are carried by a U-shaped 5 clip 22 which straddles the two bars 16 and 17 and is riveted thereto operating to impart rigidity to these bars and strips and to prevent undue spreading thereof. These lugs are preferably positioned near the pivoted ends of the latch so as to enable them 10 to be readily engaged by the thumb of the user to force the latch outwardly to release it from its engagement with the yoke member 2 as is shown in Fig. 1.

15 In the use of the invention, the trigger or latch 15 is swung inwardly into the position shown in Fig. 3, whereby the plunger 10 is locked at its extreme inward limit, it being held against outward movement by 20 the stop 12 engaging the yoke member 3 and against inward movement by engagement of said yoke member by the stop 19 on the latch 15. When the parts are so positioned, the lower or open end of the 25 mold 4 is forced down into the body of the material to be molded or measured and this is accomplished by grasping the handle 13 of the plunger rod which facilitates manipulation of the mold, the parts all being locked 30 rigidly, relatively to each other. After the mold has been filled, a partial rotation is imparted thereto to sever the material within the barrel 1 from the body of the material and the device is lifted out and the 35 material contained within the barrel is ejected by releasing the latch 15 which may be accomplished by pushing outward against one of the lugs 20 or 21. When this latch has been so released, the plunger rod is 40 moved inwardly causing the plunger 10 to force the molded material out of the barrel 1 as shown in Fig. 2, delivering the molded material in a convenient form for wrapping or other packing.

45 By so positioning the release lugs 20 and 21 on the latch 15 as to permit the outward swinging of the latch by the thumb of the hand of the user which grasps the handle, the other hand is left free to hold the barrel 50 of the mold when adjusting the plunger therein or discharging the contents therefrom, the bead 4 preventing the barrel from slipping through the hand of the user during the ejection of the molded material.

55 It will thus be seen that this latch or trigger constructed and mounted as herein shown and described is very simple and when in closed position, the plunger rod is converted into a handle for pushing the mold down into the ice cream or other material and when the device is withdrawn, the latch may be released by pushing on either of the lugs 20 or 21 which causes the latch 60 to swing outward into the position shown in Fig. 1 and permits the plunger to operate

loosely in the barrel so that by pushing inward it will eject the molded material and the plunger may then be again raised and set by the closing of the latch 15 ready for the next operation.

70 With the mold or gun equipped with this improved latch, an operator who understands the proper manipulation of the latch may mold and discharge from four or five hundred forms per hour which is about 75 double of that which can be molded without the use of this latch.

This plunger may be also used to cleanse the inside of the barrel by reciprocating it rapidly in a cleansing fluid such as hot soapy 80 water or the like.

I claim:—

1. A measuring mold comprising a barrel, a reciprocable plunger therein provided with a rod having a handle, a latch pivoted to 85 said rod, a member carried by said barrel with which said latch is designed to engage to lock the plunger against movement into the barrel in one direction, and a stop on said rod to engage said member to hold the plunger against movement in the other direction.

90 2. A measuring mold comprising a barrel, a reciprocable plunger therein provided with a rod having a handle, a latch pivoted to 95 said rod, a cross bar carried by said barrel with which said latch is designed to engage to lock the plunger against movement into the barrel in one direction, a stop on said rod to engage the other face of said member to hold the plunger against movement in the other direction, and means for swinging said latch away from said barrel-carried member.

100 3. A measuring mold comprising a barrel, a reciprocable plunger therein provided with a rod having a handle, a latch pivoted to 105 said rod adjacent said handle, a finger grip carried by said latch for swinging it away from said rod, and means carried by said barrel for engagement by said latch to lock the plunger against movement in one direction.

110 4. A measuring mold comprising a barrel, a reciprocable plunger therein provided with a rod having a handle, a cross bar carried by said barrel and spaced from the upper end thereof, said plunger rod being slidable in said cross bar, a stop carried by said rod 115 to engage the lower face of the cross bar for limiting the outward movement of the plunger, a latch pivoted to said rod to swing into and out of engagement with said cross bar for locking and releasing the plunger to lock the plunger against inward movement when in one position and to permit it to move outward when in the other position.

120 5. A measuring mold comprising a barrel, a reciprocable plunger therein provided with 130

a rod having a handle, a cross bar carried by said barrel through which said plunger rod reciprocates, means on said rod for engaging said bar to limit the outward movement of the plunger, a latch pivoted to said rod near the handle thereof and having a stirrup at its free end to straddle the rod

and to engage the cross bar when the latch is swung into closed position, and finger grips to permit the swinging of the latch ¹⁰ to release it.

In testimony whereof I have hereunto affixed my signature.

GUY E. FARMER.
